DESIGN FOR A FRAME FOR PICTURES, MIRRORS, AND THE LIKE

Doris M. Blanchette, Chicago Heights, Ill., assignor to Bradley Manufacturing Co., Chicago, Ill., a partnership composed of David Borowitz and Anne Borowitz, both of Chicago, Ill.

Application April 15, 1943, Serial No. 109,973

Term of patent 3½ years

(Cl. D29—20)

To all whom it may concern:

Be it known that I, Doris M. Blanchette, a citizen of the United States, residing at Chicago Heights, in the county of Cook and State of Illinois, have invented a new, original, and ornamental Design for a Frame for Pictures, Mirrors, and the like, of which the following is a specification, reference being had to the accompanying drawing, forming part thereof, in which—

I claim:

The ornamental design for a frame for pictures, mirrors, and the like, substantially as shown.

DORIS M. BLANCHETTE.
